UNITED STATES PATENT OFFICE

LERoy C. DOANE, OF MERIDEN, CONNECTICUT, ASSIGNOR TO THE MILLER COMPANY, OF MERIDEN, CONNECTICUT, A CORPORATION OF CONNECTICUT

DESIGN FOR A TABLE LAMP

Application filed March 23, 1932. Serial No. 43,266. Term of patent 7 years.

To all whom it may concern:

Be it known that I, LEROY C. DOANE, a citizen of the United States of America, and a resident of Meriden, in the county of New Haven and State of Connecticut, United States of America, have invented a new, original, and ornamental Design for a Table Lamp, of which the following is a specification, reference being had to the accompanying drawing forming a part hereof.

In the drawing the single figure is a perspective view of the table lamp embodying my new design, which is characterized by a plurality of conical louvers or shades spaced along the axis of the lamp.

I claim:

The ornamental design for a table lamp, substantially as shown and described.

LEROY C. DOANE.
